(57) **CLAIM**

The ornamental design for a photocatalyst module for an automobile air cleaner, as shown and described.

DESCRIPTION

FIG. 1 is a perspective view of a photocatalyst module for an automobile air cleaner of our new design;

FIG. 2 is a front view of a photocatalyst module for an automobile air cleaner of our new design;

FIG. 3 is a rear view of a photocatalyst module for an automobile air cleaner of our new design;

FIG. 4 is a left side view of a photocatalyst module for an automobile air cleaner of our new design;

FIG. 5 is a right side view of a photocatalyst module for an automobile air cleaner of our new design;

FIG. 6 is a top plan view of a photocatalyst module for an automobile air cleaner of our new design;

FIG. 7 is a bottom view of a photocatalyst module for an automobile air cleaner of our new design; and,

FIG. 8 is a perspective view from the bottom of a photocatalyst module for an automobile air cleaner of our new design.

The broken lines depict portions of the photocatalyst module for automobile air cleaner that form no part of the claimed design.
